UNITED STATES PATENT OFFICE

2,458,444

DRESSING MECHANISM

Gilbert Stewart, Detroit, Mich., assignor to Ex-
Cell-O Corporation, Detroit, Mich., a corpora-
tion of Michigan

Application February 28, 1945, Serial No. 580,125

9 Claims. (Cl. 125—11)

1

The present invention relates generally to improvements in dressing mechanisms for truing grinding wheels, and has particular reference to a new and improved dressing mechanism of the type in which the dressing tool is caused to describe forward and reverse movements to dress oppositely extending surfaces of a form contour, such as that of a wheel for grinding V-shaped threads.

One of the objects of the present invention is to provide a novel dressing mechanism having a tool actuating means of component parts which is operable to translate the tool in a dressing stroke across the abrading surface of the grinding wheel and simultaneously to move the tool reversibly from and toward the wheel axis to generate the wheel contour, and in which the strain and friction between the parts is maintained in one relative direction throughout the stroke regardless of the reverse movements of the tool, whereby to obtain improved accuracy in the dressing operation.

A more specific object is to provide a new and improved dressing mechanism which comprises a dresser slide carrying the dressing tool and movable perpendicularly toward and from the grinding wheel axis under the control of a fixed templet complementary to the form of the contour to be produced, and an actuating slide supporting the dresser slide and mounted for reciprocation in a direction inclined to the wheel axis so that one component of movement is effective to translate the dresser slide in a dressing stroke along the axis, and in which the angle of inclination of the actuating slide is so related to the form of the templet that the relative movement between the slides will remain in the same direction throughout the stroke regardless of whether the dresser slide is moving toward or from the wheel axis.

Other objects and advantages will become apparent as the description proceeds.

In the accompanying drawings,

Figure 1 is a plan view of a dressing mechanism embodying the features of my invention.

Fig. 2 is a front end elevational view of the dressing mechanism.

Fig. 3 is a fragmentary rear end elevational view.

Fig. 4 is a side elevational view.

Fig. 5 is a fragmentary transverse vertical sectional view taken approximately along line 5—5 of Fig. 1.

Fig. 6 is a fragmentary plan view on an enlarged scale of the tool holding means.

2

Fig. 7 is a fragmentary side elevational view of the tool holding means.

Fig. 8 is a fragmentary horizontal sectional view taken along line 8—8 of Fig. 5.

Referring more particularly to the drawings, the dressing mechanism constituting the exemplary embodiment of the invention may be adapted for use on various types of grinding machines and for the purpose of dressing the surfaces of different forms of grinding wheels. In the present instance, I have shown two grinding wheels G mounted in axially spaced relation on one end of a grinding spindle 1, and each having a formed cutting contour with oppositely inclined side flanks 2 and 3 and an arcuate periphery 4. Thus, the dressing mechanism is shown with two dressing tools T, one for each wheel G, and is operative to cause each tool to describe the desired wheel contour. The dressing tools T are caused to move as a unit, and hence the motion imparted by the dressing mechanism is the same for both tools, and need be described only in relation to one grinding wheel G and one associated tool T. It will be understood that the contour to be produced need not be limited to the specific form shown, but can be varied as required for different purposes.

The dressing mechanism, in the particular form shown, comprises a suitable base 5 which is adapted to be mounted in fixed position as by means of bolts 6 on a suitable support 7 forming part of a grinding machine (not fully shown), and which may be located at either side of the grinding wheel spindle 1. In instances where the front of the grinding wheel G is arranged for grinding contact with the work (not shown), the dressing mechanism preferably is located at the rear of the wheel.

The base 5 comprises a plate having spaced parallel arcuate guides 8 respectively at opposite ends and supporting a cradle 9 for angular adjustment about an axis substantially perpendicular to the axis of the wheel spindle 1. This adjustment is provided so that the plane of movement of the dressing tool T may be inclined in accordance with the inclination of the grinding wheel G to compensate for the thread lead when grinding screw threads. Suitable clamps 10 are provided on the front of the base 5 for securing the cradle 9 in position of adjustment.

Mounted on the top of the cradle 9 substantially in a horizontal plane for reciprocatory movement at an angle toward and from the axis of the spindle 1 is an actuating or base slide 11. This slide in turn carries a dresser slide 12 for

reciprocatory movement substantially perpendicularly to the spindle axis. The arrangement is such that the lateral component of the movement of the slide 11 is effective to translate the dresser slide 12 along the spindle axis and hence across the periphery of the grinding wheel G. Movement of the slide 12 toward and from the spindle axis in timed relation to the transverse movement to generate the desired wheel contour is under the control of a fixed cam, former or templet 13 on the cradle 9. The cam 13 has a contour correlated to the wheel contour to be produced, and in instances, such as shown, where the wheel contour is generally V-shaped, the cam contour is similarly shaped, and has oppositely inclined faces or surfaces 14 and 15 connected by an intermediate circular fillet 16.

The angle of inclination of the movement of the base or actuating slide 11 to the spindle axis is dependent on the shape of the wheel contour. More particularly, this angle should be somewhat less than that of either wheel flank 2 or 3 and, hence, of either cam face 14 or 15, to the wheel radius in the dressing plane. In general, the inclination of the slide 11 should be less than that of any portion of the cam contour to a perpendicular to the spindle axis.

By reason of the smaller inclination of the slide 11, the relative movement between the two slides 11 and 12 in traversing the dressing tool T across the grinding wheel G will not be reversed for dressing the opposite wheel flanks 2 and 3, but will be unidirectional. Consequently, friction and strain between the slides are never reversed during dressing contact so that a high degree of accuracy is obtained.

The slides 11 and 12 preferably have ball bearing supports. In the case of the base slide 11, the support comprises spaced parallel guide rails 17 which are removably bolted or otherwise suitably secured to the top of elevated ribs 18 formed on a central plate portion or platform 19 of the cradle 9, and which are formed in their remote or outermost sides with longitudinal V-shaped guide grooves or races 20. Two opposed guide bars 21 are bolted or otherwise suitably secured to the underside of the slide 11 inside of longitudinal depending flanges 22, and are formed in their adjacent or innermost sides with longitudinal V-shaped guide grooves or races 23. One of the guide bars 21 is laterally adjustable by means of locating screws 24 to secure proper bearing engagement regardless of wear. A plurality of balls 25, confined in carrier strips 26, are disposed in engagement respectively with the sets of opposed races 20 and 23 to complete the bearing relationship. Retainer plates (not shown), bolted to the opposite ends of the rails 17, extend outwardly across the ends of the ball raceways into the grooves 23 to confine the carrier strips 26. End plates 28 extend across and are bolted to opposite ends of the slide 11 to enclose the entire bearing support.

Any suitable means may be provided for reciprocating the slide 11. In the present instance, this means comprises a stationary nut 29 removably bolted or otherwise suitable secured to the underside of the base slide 11, and movably disposed in a longitudinal recess or groove 29a formed in the top of the platform 19 between the ribs 18. The nut 29 is in threaded engagement with a lead screw 30 on one end of a shaft 31 projecting outwardly through the rearmost plates 27 and 28 for connection to a suitable re-

versible power drive. In the present instance, the shaft 31 extends into a gear housing 32 mounted on the top of the central platform 19 of the cradle 9 and is connected through a train 5 of gears to a worm gear 33 within the housing 32. The gear 33 meshes with a worm 34 on a shaft 35 journaled in and extending laterally from the housing. The outer end of the shaft 35, in turn, is connected through a worm wheel 36 and worm 37 within a gear housing 38 to a shaft 39 driven by an electric motor 40.

The motor 40 is of the reversible type and adapted to be controlled automatically by a limit switch 41 engageable by adjustably spaced dogs 15 42 and 43 on one side of the slide 11. In the present instance, the gear housing 38 and motor 40 are suitably mounted on a bracket 44 integral with the cradle 9. The dogs 42 and 43 are so adjusted that the switch 41 will be reversibly actuated automatically at opposite ends of the reciprocation of the slide 11.

The dresser slide 12 is similarly supported on the base slide 11. More particularly, two guide rails 45 are bolted or otherwise suitably secured 25 to the top of the slide 11 in a position perpendicular to the axis of the wheel spindle 1, and are formed in their remote or outermost sides with longitudinal V-shaped guide grooves or races 46. Opposed guide bars 47 are bolted or otherwise 30 suitably secured to the underside of the slide 12, and are formed in their adjacent or innermost sides with longitudinal V-shaped guide grooves or races 48 in opposed relation to the races 46. The slide 12 is formed with depending longitudinal flanges 49 against the inner sides of which the bars 47 are positioned. A series of balls 50, confined in carrier strips 51, are disposed in engagement with the sets of opposed races 46 and 48 to complete the bearing relationship. Retainer plates 52 are bolted to opposite ends of the rails 45 to confine the carrier strips in place, and end plates 53 on the opposite ends of the slide 12 serve to enclose the entire bearing support.

The slide 12 is normally urged in one direction, for example rearwardly from the axis of the spindle 1, by suitable spring means, and is adjustably or controllably constrained against such movement by the cam 13. In the present instance, this spring means comprises a rod 54 anchored at one end to the rear end plate 53 on the slide 12, and extending longitudinally through the space between the guide rails 45 on the slide 11. A collar 55 is secured to the rod 54 intermediate its ends. A coiled compression spring 56 encircles the rod 54, and is seated at opposite ends respectively against a guide sleeve 53a abutting the front retainer plate 52 and the collar 55 to urge the slide 11 rearwardly.

The cam or templet 13 is mounted in fixed position on the cradle 9 for cooperative engagement by the slide 12, and preferably is in the form of a plate removably supported in a bridge structure 57 spanning over the slide assembly. More particularly, the bridge structure 57 comprises two spaced upstanding brackets or standards 58 fixed on the top of the cradle 9 at opposite sides of the platform 18 and extending parallel to the slide 11. A bridge plate 59 is bolted to the upper ends of the standards 58 and extends in vertically spaced relation over and across the slide assembly. The plate 59 is formed with an opening 60 normally closed by a removable cover 61, and the cam 13 is suitably bolted to the underside of the cover in position within the opening.

The dresser slide 12 is operatively associated with the cam through a suitable follower. In the present instance, this follower comprises a vertical pin 62 on the slide 12, and engaging the face of the cam 13. It will be seen that as the base slide 11 is caused to move in opposite directions, the spring 56 will maintain the follower 62 in bearing engagement with the cam 13, and the latter will follow the cam contour so as to cause the dressing tool T to describe the desired path of cutting engagement with the periphery of the grinding wheel G.

The dressing tools T, or either of them if only one is provided, may be adjustably supported on the forward end of the slide 12 in any suitable manner. In the present instance, the means for this purpose comprises a tool support 64 for each tool T supported on a V-guide 65 on the forward end of the slide 12 for transverse adjustment by means of an adjusting screw 66, and adapted to be locked in position of adjustment by a set screw 67. This independent transverse adjustment of the supports 64 for the respective dressing tools T permits the latter to be spaced axially of the drive spindle 1 in accordance with the spacing of the grinding wheels G. Each support 64 is formed with a bore 68 opening to the forward side and closed at the rear end. A cylindrical tool holder 69 is slidably received in the bore 68, and is constrained against rotation by a spline screw 70. The holder bears endwise against, and is adjustable by, a backing screw 71 threaded axially into the closed end of the bore 68, and is adapted to be secured in position of adjustment by a set screw 72 engageable with a flat thereon. The forward or outer end of the holder 69 is formed with an axial bore or socket 73 receiving the shank 74 of the tool T secured therein by a set screw 75.

In operation, assuming that the adjusting slide 11 is at its forward limit of travel to position the dressing tools T to the right of their respective grinding wheels G preparatory to a continuous dressing stroke from right to left, the motor 40 is operated in a direction to retract the slide along the line A—A. In the initial movement, the dresser slide 12 is traversed to the left and also outwardly in timed relation as determined by the surface 14 of the cam 13. As a result, each tool T is caused to dress the flank 2 of the associated wheel G. When the follower 62 reaches the end of the cam surface 14, and traverses the fillet 16, each dressing tool T will dress the periphery 4 of the associated wheel G. As the follower 62 traverses the cam surface 15, the slide 12 will be moved forwardly, and each tool T will dress the flank 3 of the associated wheel G.

By reason of the angular disposition of the slide 11, the relative movement between the slides 11 and 12, although varying in rate, is always in the same direction. Thus, during the initial movement to dress the flank 3, the slide 12, although being retracted from the wheel G, is actually moving forwardly relative to the slide 11 due to the fact that the angle of inclination of the latter is less than that of the cam surface 14. Obviously, this relative movement is not changed in direction as the follower 62 moves across the cam fillet 16. As the follower 62 moves across the cam surface 15, the slide 12 is not only moved forwardly toward the grinding wheel G, but continues to be moved forwardly relative to the actuating slide 11.

At the end of the cutting traverse, the dog 43 actuates the switch 41 to effect reversal of the

motor 40, and thereupon the direction of the slide 11 is reversed to return the latter to initial position. During the initial movement, as the follower 62 moves across the cam surface 15, the slide 12 moves rearwardly from the grinding wheel G and also rearwardly relative to the slide 11. This condition is not changed as the follower 62 moves across the cam fillet 16. During the final movement, as the follower 62 moves across the cam surface 14, the slide 12 again moves toward the grinding wheel G, but continues to move rearwardly relative to the base slide 11 by reason of the aforesaid angular relationship.

I claim as my invention:

1. A grinding wheel dressing mechanism comprising, in combination, a base formed with transverse spaced parallel arcuate guides on the top, a cradle mounted on said guides for rotary adjustment about a predetermined axis, an actuating slide having a ball bearing support on said cradle for reciprocation in a direction inclined to said axis, reversible drive means on said cradle for translating said slide and including a lead screw in threaded engagement with a nut on the underside of said slide, upstanding standards on said cradle at opposite sides of said slide, a bridge plate connected to said standards and extending in spaced relation over said slide, a dresser slide having a ball bearing support on said actuator slide for reciprocation in a direction parallel to said axis, a contour cam removably mounted on the underside of said bridge plate and having a form with oppositely inclined faces complementary to the form to be produced on the grinding wheel, a follower on said dresser slide engaging said cam, spring means urging said follower constantly in engagement with said cam, and a dressing tool mounted on and movable with said dresser slide, the angle of inclination of said actuating slide being less than that of the similarly inclined face of said cam, whereby for movement of said actuating slide in one direction the movement of said dresser slide relative thereto will be in one direction regardless of reversal of movement of said dresser slide relative to said cradle.

2. A grinding wheel dressing mechanism comprising, in combination, a base formed with transverse spaced parallel arcuate guides on the top, a cradle mounted on said guides for rotary adjustment about a predetermined axis, an actuating slide mounted on said cradle for reciprocation in a direction inclined to said axis, reversible drive means for translating said slide, a bridge on said cradle and having a cross member extending over said slide, a dresser slide mounted on said actuator slide for reciprocation in a direction parallel to said axis, a cam on the underside of said member and having a form with oppositely inclined faces complementary to the form to be produced on the grinding wheel and extending crosswise of said dresser slide, a follower on said dresser slide, spring means for maintaining said follower in engagement with said cam, and a dressing tool mounted on and movable with said dresser slide, the angle of inclination of said actuating slide being less than that of the similarly inclined face of said cam, whereby upon movement of said actuating slide in either direction the movement of said dresser slide relative thereto will continue in one direction regardless of reversal of said dresser slide relative to said cradle.

3. A grinding wheel dressing mechanism comprising, in combination, a supporting base, an

actuating slide having a ball bearing support on said base for reciprocation in a predetermined direction adapted to be disposed in inclined relation to the wheel axis, reversible drive means for translating said slide, a bridge on said base and having a cross member extending over said slide, a dresser slide having a ball bearing support on said actuating slide for movement in a direction inclined to said first mentioned direction and adapted to be disposed in perpendicular relation to said wheel axis, a contour cam on said member and having a form with oppositely inclined sections and extending crosswise of said dresser slide, a follower on said dresser slide, spring means for maintaining said follower against said cam, and a dressing tool mounted on and movable with said dresser slide, the angle of inclination of said actuating slide being less than that of the similarly inclined section of said cam, whereby upon movement of said actuating slide in either direction the relative movement between said slides will be maintained in one direction.

4. A grinding wheel dressing mechanism comprising, in combination, a supporting base member, an actuating slide mounted on said base member for reciprocation in a predetermined first path, a dresser slide member adapted to support a dressing tool and mounted on said actuating slide for movement in a predetermined second path acutely inclined to said first path, a contour cam on one of said members and extending generally crosswise of said dresser slide, said cam having a contour with sections inclined oppositely with reference to said second path, the relative inclination between said paths being less than that of the contour section which is inclined in the same general direction, and a follower on the other of said members constantly engaging said cam.

5. A grinding wheel dressing mechanism comprising, in combination, a supporting base, an actuating slide mounted on said base for reciprocation in a predetermined first path, a bridge on said base and extending over said slide, a dresser slide adapted to support a dressing tool and mounted on said actuating slide for movement in a predetermined second path acutely inclined to said first path, a contour cam on said bridge and extending generally crosswise of said dresser slide, and a follower on said dresser slide constantly engaging said cam, the inclination to said second path to said first path being slightly less than that of any similarly inclined portion of the form of said cam.

6. A dressing mechanism comprising, in combination, a supporting base, an actuating slide mounted for reciprocation on said base along a predetermined path and having a generally transverse component of movement in one direction inclined to said path and a generally longitudinal component of movement perpendicular to said transverse component, a dresser slide mounted at an angle on said actuating slide for movement therewith along said transverse component and for relative movement thereon along said longitudinal component, a contour cam fixed on said base and having a cam face extending transversely of said dresser slide and coacting therewith to determine the position of said dresser slide relative to said base along said longitudinal component at all points along said transverse component, said cam face including cam sections angularly inclined in opposite directions relative to the direction of said longi-

tudinal component and at angles greater than or opposite to the angle of relative direction of movement of said slides so that upon movement of said actuating slide in either direction the relative movement of said slides along said longitudinal component will continue unidirectionally regardless of reversal of movement of said dresser slide relative to said base.

7. A dressing mechanism comprising, in combination, a base, an actuating slide reversibly slidable on said base, a dresser slide adapted to support a dressing tool and being reversibly slidable on said actuating slide, the directions of movement of said slides being relatively inclined at an acute angle, cam means for controlling the longitudinal movement of said dresser slide on said actuating slide while permitting movement of said dresser slide laterally with said actuating slide, all portions of the cam face of said cam means being inclined to the direction of movement of said dresser slide on said actuating slide at an angle greater than said acute angle.

8. A dressing mechanism comprising, in combination, a base, an actuating slide reversibly slidable on said base, a dresser slide adapted to support a dressing tool and being reversibly slidable on said actuating slide, the directions of movement of said slides being relatively inclined at an acute angle, cam means for controlling the longitudinal movement of said dresser slide on said actuating slide while permitting movement of said dresser slide laterally with said actuating slide, and two dressing tools mounted on one end of said dresser slide in laterally spaced relation for movement therewith, and being independently laterally adjustable thereon to vary their location and relative spacing.

9. A grinding wheel dressing mechanism comprising, in combination, a supporting base member, an actuating slide mounted on said base member for reciprocation in a predetermined direction adapted to be disposed in inclined relation to the wheel axis, means for translating said slide on said base member, a dresser slide member mounted on said actuating slide for movement in a direction inclined to said first mentioned direction and adapted to be disposed in perpendicular relation to said wheel axis, a contour cam on one of said members and having a form including oppositely inclined sections and extending crosswise of said dresser slide member, a follower on the other of said members, and spring means for maintaining said follower against said cam, said dresser slide member being adapted to support a dressing tool for movement therewith, the angle of inclination of said actuating slide being less than that of the similarly inclined section of said cam, whereby upon movement of said actuator slide in either one direction said dresser slide member will be reciprocated relative to said base member in accordance with the contour of said cam while maintaining relative movement to said actuating slide in one direction.
